UNITED STATES PATENT OFFICE

2,528,913

PORTABLE CRUCIFIX AND CASE

Allan Robinson, Boston, Mass.

Application May 11, 1948, Serial No. 26,382

7 Claims. (Cl. 206—19)

1

The present invention relates to a portable crucifix and a case for it, which may serve in a number of ways in combination with the crucifix. Sometimes it is desired to wear the crucifix as an emblem, while at other times it is desired to mount the crucifix on an altar, use it alone, or in combination with the case as an emblem, or simply to use the case as a holder for the crucifix.

In the present invention the container, or case, together with the crucifix, serves all these purposes and therefore provides or gives extreme utility to the religious article made according to the present invention. The merits and advantages of the present invention will be more readily understood from the description in the specification annexed hereto and taken in connection with the drawings illustrating the embodiment of invention in which.

Figure 1 shows the front elevation of the crucifix held face forward in the casing.

Figure 2 shows the casing in the same position as Figure 1 with the crucifix removed. Figure 3 shows a sectional view taken on the line 3—3 of Figure 2.

Figure 4 shows a side view as seen from the side of Figure 1.

Figure 5 shows a view of the casing serving as an altar with the crucifix placed therein, and

Figure 6 shows a plain view of the casing as an altar with the crucifix removed. In the arrangement indicated in the figures the element 1, which may be called the casing, may be molded from a hard plastic material in any usual manner. This may be suitably colored in black, white or other combinations as may be desired.

The element 1 may be level on one face, as, for instance, the face 2, which will, therefore, serve as the bottom in the position shown in Figure 5. The face, 2, of the element is recessed in moulding or by carving or cutting as indicated more particularly in Figure 2 wherein the recess is formed by the walls 3 and 4 extending vertically, and the walls 5 and 6 extending horizontally to form the shape in which a crucifix will fit.

As will be noted from Figure 2 and the section of Figure 3, the recess is deepened in the vicinity of the intersection of the cross bars by the successively deepened cuts, 7 and 8, in the cross arm recesses about their intersection providing sufficient room to receive the Christ figure and sign when the crucifix is faced about with the figure on the inside. A concave cavity of circular shape is provided about the intersection of the cross bar

2

recesses both for appearance and to permit the crucifix to be picked up from the base. For the same reason the base of the recess 9 between the walls 3 and 4 is deepened by successive deeper cuts as indicated at 10 and 11. When the figure is faced inward, the opposite face of the crucifix is flush with the face of the casing 2.

In either position, the upright bar 12 of the crucifix will have its lower end, on which there 10 is a small "boss" 13, bear against the central section of the wall of the slot 14 and at the top the cross bar 12 will have its shoulders 15 rest snugly in the corners 16 and 17 of the casing 2.

The cross bar 12 terminates in a narrow stem 15 18 which projects from the top of the casing and through which stem a hole 19 may be made so that the whole assembly or the crucifix alone, if desired, may be suspended as a necklace or the like, or from any other suitable place.

20 The slot 14 at the base of the casing serves to provide some flexibility and springiness so that the cross may be held in place without any danger of its slipping out. The opposite face of the casing, which may be called the top face, when used 25 as indicated in Figures 5 and 6, may be formed in the shape of a miniature altar with a raised platform 20 in which suitable recess 21 is formed to receive the bottom end 22 of the crucifix when that is stood upright in the recess 21.

30 For traveling purposes the crucifix will be turned with the emblem 23 face inward in which case the surface of the cross will be flush with the face 2 and make a convenient article which can be readily carried in the pocket or other place without danger of damage to it. The article may be attractively designed with a light colored plastic crucifix, contrasting container or case and a gold or silver emblem.

Having now described my invention, I claim:

1. A religious article comprising a base having a recess in the form of a crucifix formed in one face thereof and a crucifix adapted to fit in said recess, said base being recessed on the edge and extending into the recess for the top end of the longer bar of the crucifix and aligned with the recess for the longer cross bar, said crucifix having narrowed end section projecting from the top end of the longer cross bar and extending beyond the edge of the case, said end section having means for suspending the article.

2. A religious article comprising a base element recessed in the form of a crucifix on one face, a crucifix adapted to fit snugly therein with an extension from the top of the longer cross bar of the crucifix projecting from the edge of the case

and means in said extension for suspending said case and crucifix.

3. A religious article comprising a base element recessed in the form of a crucifix on one face, a crucifix adapted to fit snugly therein with an extension formed as a narrow projection extending from the top end of the longer cross bar, said projection fitting into a corresponding recess extending from the edge of the base and merging into the first recess.

4. A religious article comprising a base element recessed in the form of a crucifix on one face, a crucifix adapted to fit snugly therein with an extension from the top of the longer cross bar of the crucifix projecting from the edge of the case, means in said extension for suspending said case and crucifix, the top surface of said base formed as an altar with a recess in the uppermost surface thereof adapted to receive the bottom end of the long bar of the crucifix.

5. A religious article comprising a base element recessed in the form of a crucifix on one face, a crucifix adapted to fit snugly therein, said base having a slot made with one wall extending from the end wall of the recess corresponding to the lower end of the long cross bar, providing spring tension against the end of the crucifix.

6. A religious article comprising a base element recessed in the form of a crucifix on one face, a crucifix adapted to fit snugly therein, said

base having a slot made with one wall extending from the end wall of the recess corresponding to the lower end of the long cross bar, providing spring tension against the end of the crucifix and the bottom end of the longer cross bar having a boss bearing against said end wall of the recess.

7. A religious article comprising a base element recessed in the form of a crucifix on one face, a crucifix adapted to fit snugly therein, the recess for said crucifix being deeper in the cross bars nearer their intersection for providing for a projecting figure from the face of the crucifix and a concave circular recessed section made in the face of the base concentric with the point of intersection of the cross bars of the crucifix, said last recess being deep enough to expose the side wall of the crucifix in the vicinity of the intersection.

ALLAN ROBINSON.
